(57) **CLAIM**

The ornamental design for an angled rack, as shown and described.

DESCRIPTION

FIG. 1 is a rear perspective view of my new design for an angled rack;

FIG. 2 is a front elevation view of my new invention;

FIG. 3 is a rear elevation view of my new invention;

FIG. 4 is a top plan view of my new invention;

FIG. 5 is a bottom plan view of my new invention;

FIG. 6 is a left side elevation view of my new invention, wherein a right side elevation view is a mirror image thereof; and,

FIG. 7 is a left side perspective view of my new invention. The broken lines indicating feet and an off road vehicle are for the purposes of illustration and form no part of the claimed design.
